CATTLE CHUTE

Henry C. Whitworth, Scott City, Kans.

Application January 13, 1949, Serial No. 70,637

4 Claims. (Cl. 119—99)

1

This invention relates to a stock chute and more particularly to a chute that is adapted to confine animals such as cattle, horses and the like for purposes of dehorning, branding, and so forth.

Chutes for the above-mentioned purposes have been previously designed and the present application is intended to set forth improvements in the art as represented by the previous designs. Specifically this application provides improvements in the design for a stock chute as shown in my previous Patent No. 2,564,317, issued August 14, 1951. The improvements herein incorporated are intended to make previous designs for stock chutes and the like more serviceable, easier to operate, more sturdy and more efficient.

It is an object of this invention to provide a stock chute of sturdy and rugged construction that may be economically constructed and assembled.

It is a further object of this invention to provide a stock chute incorporating novel improvements and arrangements for positioning and pivoting the side walls and side bars thereof.

It is another object of this invention to provide bars in said pivoted sides that may be moved out of a locked position in order to more readily reach various portions of the animal's body and to further provide means for locking and disengaging said side bars as desired.

Another object of this invention is to provide a front gate for a stock chute that may be vertically adjusted and that carries novel means for adjustably positioning a nose bar clamp.

A still further object of this invention is to provide novel means for supporting and adjusting the position of a head yoke arranged for cooperative use with said front gate which novel means is inclusive of a foot adjusted catch.

Another object of this invention is to provide a novel lever arrangement for moving the pivoted sides of said stock chute and further novel means for adjusting the position of said lever mechanism.

The foregoing and further objects and advantages of this invention will be apparent from the following description and drawings in which:

Fig. 1 represents a front elevational view in partial section showing the general arrangement of a stock chute and further showing the positioning of the pivoted sides when released and when engaged;

Fig. 2 is a side elevational view further showing the features of this invention;

Fig. 3 is an enlarged side elevational view in

2

partial section showing the head yoke elevating gear;

Fig. 4 is an enlarged side elevation in partial and in reduced section showing the arrangement of a hand wheel control for adjusting the elevation of said head yoke and further showing a catch and ratchet arrangements with foot control for maintaining the position of said head yoke.

10 Fig. 5 is an enlarged front elevational view further showing the notch and ratchet arrangement of Fig. 4;

Fig. 6 is an enlarged side elevational view showing an arrangement of elements as used to clamp the nose bar in place;

Fig. 7 is an enlarged elevational view in partial section of the bracket and notch clamp arrangement shown in Fig. 6;

Fig. 8 is an enlarged front elevational view of the notch clamp shown in Figs. 6 and 7;

Fig. 9 is a slightly enlarged plan view in partial section showing the means used for engaging the opposite end of the nose bar;

Fig. 10 is a slightly enlarged plan view in partial section further showing the elements of the door catch as shown in Fig. 1;

Fig. 11 is an enlarged elevation showing the use of a pivoted side positioning member;

Fig. 12 is a cross sectional view taken along the line 12—12 of Fig. 11 further showing the construction of the pivoted side positioning member of Fig. 11;

Fig. 13 is an enlarged elevation in partial section showing a slide arrangement for the head yoke of Fig. 1;

Fig. 14 is an enlarged side elevation showing the engagement of the head yoke in the upright guide rails;

Fig. 15 is a top plan view showing the arrangement of the upper support rail and side bars;

Fig. 16 is an elevation of the side bar and support rail of Fig. 15;

Fig. 17 is a cross sectional view taken along the line 17—17 of Fig. 15 further showing the arrangement of the cross bars and support rail; and

Fig. 18 is an elevational perspective view showing a lever engaging member and separate spring actuated means for maintaining the lever in its engaged position.

Briefly stated the present invention provides a stock chute of generally rectangular frame structure upon which a pair of pivoted sides are arranged. A lever arrangement is provided for moving the pivoted sides inwardly to hold an

animal therebetween or outwardly to release the animal and, for the purpose of adjusting the sides in accordance with the size of the animal to be held, a notch and latch arrangement is used to adjust the location of the pivot about which the sides are moved. For the purpose of further enclosing the animal in the chute, a swinging front gate and an elevatable back gate are provided.

In order to hold the head of the animal, the front gate is provided with means for vertically positioning the gate, and further means for engaging and holding a nose bar in adjusted and clamped position. A head yoke which may be raised and lowered by a hand wheel is arranged for sliding engagement in the side rails of the frame structure and a foot actuated catch is provided to hold the head yoke in adjusted position. The nose bar previously mentioned is arranged for adjustable engagement in separate pivots mounted on the swinging door and the opposite end of the nose bar is engaged in a clamping mechanism that allows free adjustment of the positioning thereof. In addition, said clamping mechanism provides a lever release so that the pressure exerted by the nose bar on the nose of the animal may be readily released. The side bars which are mounted in the pivoted sides of this cattle chute are of novel construction and utility. These bars are provided with a T-shaped and arranged cross bar of such dimension that it will fit snugly over the outside edges of the support rail. A slot is cut in the top support rail so that when the bars are raised upwardly and turned through an arc they may then be lowered through the slot to an alternate position. In addition, if so desired, the bars may be raised and turned in another direction to disengage a catch formed on the bars so that the bars may be moved all the way out of and away from the support rails.

Referring now to the drawings the novel features of this invention as set forth above will be described in detail. In Fig. 1 it will be seen that this invention provides a stock chute generally designated 11 which is made up of a general frame structure. The frame structure of stock chute 11 comprises a base platform support 12 upon which upright channel members 13 are formed. Angle members 14 joined together in a general A-frame arrangement interconnect the separate upright channel members 13 to complete forward frame support 16 and rear frame support 17. Flat plates 18 are welded to angle members 14 to provide support for bearing supports 19. Bearings 19 further provide support for a longitudinal lever support shaft 21 which interconnects the front and back frame supports 16 and 17 respectively.

Movable sides 22 are arranged to move or swing inwardly and outwardly about pivots 23 and pivots 23 are adjustably positionable on platform 12. The means for adjusting the positioning of pivots 23 and therefore the means for adjusting the distance between the lower extremities of the movable walls 22 includes the use of a notched bar 24 which is slidably engaged between guide rails 26 rigidly mounted on platform 12. Pivoted latches 27 which are held by clamp members 28 are arranged for engagement with the notches 29 of notch bars 24. Thus whenever it is desired to change the positioning of the movable walls 22, latches 27 will be raised out of the engaged position, the notched bars 24 will be moved inwardly or outwardly as desired, and the

latches 27 will again be engaged to hold the pivots 23 in the desired position.

The upper extremities of the movable walls 22 are interconnected by a parallel linkage mechanism to the lever support shaft 21. The aforementioned parallel linkage is inclusive of short links 31 pivotally connected to the upper extremities 32 of movable walls 22 by pivot pins 33 and further pivotally connected to rotating bars 34 by pivot pins 36. Rotating bars 34 are engaged with lever support shaft 21 such that rotation of the shaft 21 will cause rotation of the bars 34.

In order to rotate the shaft 21 and thereby cause the upper extremities 32 of the movable walls 22 to be moved toward or away from each other as necessary to hold or release the animal being treated, a lever extension 37 is used which is engaged with the shaft 21. The lever 37 has a catch member 38 angularly mounted thereon. Catch member 38 is arranged for engagement in the notches 39 formed in the lever positioning rack 41 and lever positioning rack 41 is welded to the upright frame member 13. At the upper and lower extremities of the rack 41, cylindrical tube portions 42 are welded to the upper extremities of the rack 41 and a rod member 43 is arranged for translatory movement in tube members 42. Rod member 43 is bent to parallel the plane of lever travel and springs 44 are provided for urging the rod into engagement with the lever 37. By means of this arrangement it will be seen that whenever the lever 37 is moved to the desired position and engaged in the selected notch 39, the rod 43 will tend to hold the lever in such selected position, and whenever it is desired to move the lever, the lever must first be moved sideways to overcome the tension of springs 44.

Other novel features of the movable side walls are shown in Figs. 2, 15, 16 and 17. In these figures the construction and arrangement of the walls themselves are fully set forth. In Fig. 2 it will be seen that the movable side walls comprise a framework made up of upright members 46 and upper and lower guide rails 47 and 48 respectively. In addition, below the lower guide rail 48 the upright members 46 are joined together by a metal plate 49 which serves as a kick panel whenever animals are held in the chute. Upper and lower guide rails 47 and 48 respectively provide support for side bars 51. In the embodiments shown, the bars 51 are of a generally tubular cross section and they are arranged for engagement in circular holes 52 cut in the upper and lower guide rails 47 and 48. To keep the side bars 51 from falling through the upper rail support 47, a cross rod 53 is welded to the upper extremity of side bar 51 in a general T formation and the ends 54 of rod 53 are down-turned in such manner as to engage the sides of the upper support rail 47 when the T bar is turned so as to be across the support rail 47. An elongated slot 56 is cut in the upper support rail 47 so that the cross rod 53 will pass downwardly through the support rail after it has been raised and rotated out of its transverse position. When so raised and rotated side bar 51 may be lowered until the lower extremity of the side bar 57 comes into engagement with the platform 12. This alternate position for the side bars is shown in Fig. 2. As shown in this figure it will be apparent that the lowering of the side bar 51 will greatly facilitate the branding of an animal held between the movable side walls 22. If it is desirable to completely remove any of the side bars

51 the bar may be raised, rotated through approximately 45° until pin 58 passes through slot 56 and then the bar may be taken completely out.

As shown in Figs. 1, 2, 6, 7, 8, 9 and 10, the cattle chute of this invention is provided with a front gate 59. Gate 59 is mounted on the upright channel member 13 through use of a hinge rod 61 which is rotatably engaged in upper and lower bearing sockets 62. The gate 59 itself is formed integrally with tubular portions 63 which are adapted to fit around hinge rod 61. In order to allow for adjustments in the elevation of the door, tubular portions 63 fit loosely about hinge rod 61 so that the gate 59 may be raised or lowered as desired with respect to the hinge rod 61. In Fig. 1 the gate is shown in its lowest position. However, from this view it will be apparent that if a large animal is to be placed in the chute, the gate can be raised and repositioned at a higher elevation by loosening set screw 64, raising the gate with respect to rod 61, and again tightening said screw 64 to again attach the gate to the rotatable hinge rod 61.

Structurally the gate itself is made up of a flat plate of metal 66 to which suitable reinforcing members such as tubular piece 67 are welded. As shown in Fig. 1 tubular piece 67 has a downwardly extending U-shaped notch 68 into which the head of an animal may be placed. For the purpose of securing the door in its closed position, a spring actuated latch 69 is provided. Latch 69 is made up of an elongated rod 71 to which a catch 72 is affixed. Rod 71 passes through a brace 73 which serves further as a spring stop. A spring 74 is arranged at one end of rod 71 so that it may be compressed between brace 73 and a collar 76 formed on rod 71. A handle 77 attached to rod 71 is provided to aid the compression of spring 74 when it is desired to release catch 72. When in the closed position the spring 74 tends to urge the catch 72 into engagement with the outer flange 78 of a channel piece 79 which is welded to upright channel member 13.

A nose bar 81 is provided for cooperative positioning with the notch 68 of door 59 and is arranged to be secured in any of several adjusted positions. For the purpose of making major adjustments in the positioning of nose bar 81, a plurality of socket members 82 are welded to a forwardly extending brace 83. Socket members 82 are so arranged that a downwardly turned end 84 of nose bar 81 may be pivotally engaged in any one of the separated sockets 82 as desired. This arrangement for making major adjustments in the positioning of the nose bar 81 is best shown in Fig. 9. Figs. 6, 7 and 8 show the arrangement of a mechanism provided to make minor adjustments in the positioning of nose bar 81. In this arrangement a catch 86 which is welded to an extremity of the nose bar 81 is arranged for engagement in the notches 87 of a pivoted notch bar 88. Pivoted notch bar 88 is supported by structural members 89 formed integrally with door 59 and is arranged for rotation about pin 91. Guide members 92 extend outwardly from the door 59, and tubular section 93 is affixed to the outer extremities thereof. Guide members 92 are separated sufficiently so that notched bar 88 may be rotated therebetween and a spring 94 received in tubular section 93 acts against notch bar 88 to urge the bar upwardly past the guide members 92. A rod 96 formed on the lower surface of notch bar 88 is adapted for reception in cylindrical piece 93 and it acts as a further

guide for directing the action of spring 94. Inasmuch as the notch bar 88 is urged upwardly the catch 86 formed on nose bar 81 will be engaged in a selected notch 87 of the notch bar 88 as desired. Whenever it is desired to reposition the nose bar 81 or whenever it is desired to release the nose bar, a separate lever 97 mounted for pivotal movement about a pivot 98 may be moved downwardly. When lever 97 is moved downwardly, an angularly disposed extension 99 of lever 97 is urged into engagement with notch bar 88. This engagement causes the notch bar 88 to be moved downwardly past the guide members 92 into a retracted position. When the notch bar 88 is in a retracted position, nose bar 81 may be swung outwardly to release the nose of the animal.

As further shown in Fig. 1 a head yoke 101 is provided which may be urged downwardly to hold the head of the animal. The features and operation of yoke 101 are best illustrated in Figs. 3, 4, 5, 13 and 14. In Figs. 13 and 14 guide followers 102 which are attached to the ends 103 of head yoke 101 are shown as received for reciprocal motion between the flanges 104 of upright channel member 13.

The mechanism for raising and lowering the head yoke bar 101 and for adjustably positioning the same is best shown in Figs. 1, 3, 4, and 5. In these figures it will be seen that a punched rack 105 is attached to the head yoke 101 by bolts 105 or the like. Punched rack 105 is arranged to cooperatively engage the spokes 107 of rotary disc 108 and disc 108 is attached to a rotating shaft 109 which is in turn journaled in bearings 111 supported by plate 18. A hand wheel 112 which is likewise engaged with shaft 109 is provided to rotate disc 108 and therefore to position head yoke 101. A ratchet member 113 likewise attached to shaft 109 is used together with a foot actuated catch 114 to hold the head yoke in any selected and desired position. Catch 114 is engaged or released by means of a pivoted foot pedal 116 which urges a rod 117 attached to catch 114, to move upwardly or downwardly as desired.

A back gate 118 is also provided to further enclose any animals driven into the chute. Gate 118 is adapted for reciprocal movement between the channel members 13 comprising the back frame 17. To raise or lower gate 118 a pulley is attached to the plate 18 and a cable 119 or the like is passed through the pulley and tied to the gate 118.

While one separate embodiment of my invention has been shown and described, it will be apparent from the foregoing description and the drawings that my invention is adaptable to various arrangements and changes. All such arrangements and changes are considered to be within the scope of this invention as set forth in the hereunto appended claims.

What is claimed is:

1. A cattle chute comprising a platform, a channel frame structure having substantially arch-shaped frame members at the front and rear ends thereof, bearing members mounted on said arch-shaped members, a longitudinal shaft rotatably suspended between said bearing members, side wall sections pivotally supported on said platform, linkage means connecting upper extremities of said side wall sections to said longitudinal shaft, lever means connected to said linkage means for moving said side walls toward and away from each other, a gate slide formed of said channel frame members at the rear end of said chute, a gate mounted for reciprocal move-

ment along said slide to adjustable elevations providing a closure for the rear end of said chute, a hinge rod at the front end of said frame, a door adapted to close off the front end of said chute, means for securing said door to the hinge rod in adjusted elevational positions for rotating movement about the pivot axis of said hinge rod, a slide formed of said channel frame members at the front end of said chute, a head yoke reciprocally mounted in said slide for cooperative use with said door, a gear and rack mechanism for raising and lowering said yoke, and a ratchet and catch mechanism for locking said yoke in desired positions.

2. A cattle chute comprising a platform, a channel frame structure having substantially arch-shaped frame members at the front and rear ends thereof, bearing members mounted on said arch-shaped members, a longitudinal shaft rotatably suspended between said bearing members, side wall sections pivotally supported on said platform, linkage means connecting upper extremities of said side wall sections to said longitudinal shaft, lever means connected to said linkage means for moving said side walls toward and away from each other, a gate slide formed of said channel frame members at the rear end of said chute, a gate mounted for reciprocal movement along said slide to adjustable elevations providing a closure for the rear end of said chute, a hinge rod at the front end of said frame, a door adapted to close off the front end of said chute, means for securing said door to the hinge rod in adjusted elevational positions for rotating movement about the pivot axis of said hinge rod, a slide formed of said channel frame members at the front end of said chute, a head yoke reciprocally mounted in said slide for cooperative use with said door, a gear and rack mechanism for raising and lowering said yoke, a ratchet and catch mechanism for locking said yoke in desired positions, a plurality of socket members mounted on said door, a nose bar having one end thereof adapted for selective engagement in said sockets, and an adjustable spring loaded catch mounted on said gate adapted to engage the opposite end of said nose bar.

10

20

25

30

35

40

45

3. A nose engaging apparatus for cattle chutes, comprising a brace member at one end of said chute having a plurality of pivot engaging socket members thereon, a nose bar having a downwardly turned end for selective engagement in said pivot engaging socket members, oppositely disposed guide members at the said end of said chute, a catch member having a plurality of notches therein rotatably mounted between said guide members, a spring for urging the notches of said catches into engagement with said nose bar, and a lever mechanism for engagement with said catch to move said catch out of engagement with said nose bar.

4. Apparatus for adjusting the positioning of the longitudinal side walls of a cattle chute having support members so as to accommodate large and small animals, comprising pivot members on the lower ends of said side walls, guide rails mounted on said support members adjacent the lower ends of said side walls and transversely to said longitudinal side walls, a bar attached to each of said pivot members having notches therein slidably engaged between said guide rails, and a rotatable catch for selective engagement with the notches of said bar to hold said bar and side wall pivot in desired position.
